SAFETY GUARD

Samuel Chilson, Brooklyn, N. Y.

Application September 13, 1932, Serial No. 632,881

7 Claims. (Cl. 94—38)

My invention relates to a new and improved safety guard.

One of the objects of my invention is a simple and efficient device which can be readily collapsed into a small space so that the device can be conveniently shipped and handled.

Another object of my invention is to provide a simple and efficient device which can be readily set up in order to guard an opening in the floor of a building, while permitting ready access to said opening.

Other objects of my invention will be set forth in the following description and drawings which illustrate a preferred embodiment thereof, it being understood that the above general statement of the objects of my invention is intended to generally explain the same, without limiting it in any manner.

Fig. 1 is a front elevation showing part of the device in operative position, and showing part of the device in inoperative position. It is to be understood that the workmen can gain access to the opening, by moving parts of the device to the inoperative position.

Fig. 2 is a detail elevation showing how certain of the guard members overlap and interengage with each other.

Fig. 3 is a detail perspective view showing how one of the turnable arms of the device is locked in operative position.

Fig. 4 is a top plan view of Fig. 3.

Fig. 5 is a top plan view showing how the turnable arm which is illustrated in Fig. 3, is held in the inoperative position.

Fig. 6 is a top plan view of the device, when it is set up and is in the operative position.

Fig. 7 is a front elevation showing how the entire device has been collapsed, so that the same can be stored or shipped.

The safety device comprises a series of units which can be conveniently assembled around the edge of the opening.

Referring to Fig. 6, each of these units comprises a base 1 to which a T-shaped standard 2 is secured in any suitable manner, such as by welding or the like. The base 1 is provided with openings through which fastening devices 3 can be inserted, in order to connect the base 1 to the floor of the building.

The head of the standard 2 is provided with a U-shaped member 4. Said member 4 is connected to the head of the standard 2 by any suitable fastening devices, or by welding or the like.

As shown in Fig. 6, each U-shaped retaining member 4 is provided with outwardly bent lugs 4a.

Referring to Fig. 1, each of the edges of the standard 2 is provided with brackets 5 and 5a. Said brackets 5 and 5a are turnably secured to the standard 2, by means of hinges 6 which are secured to the standard 2 by means of any suitable fastening devices, welding or the like. Hinge-pintles 6a pass through the hinges 6 and through ears which are formed in the brackets 5 and 5a. Upper guard members 7 which are made of angle irons, are turnably secured to the brackets 5 and 5a, by means of pivot pins 8. The outer face of each bracket 5 and 5a is provided with stop members 9, so that the upper guard members 7 are retained in horizontal position.

As shown at the right-hand side of Fig. 1, each upper guard member 7 may be turned upwardly and away from the horizontal position, so that it will abut the corresponding lateral face of the retaining member 4. In this inoperative position, the guard member 7 also abuts the corresponding lug 4a, so that lateral movement of said guard member 7, with respect to its bracket, is limited or prevented.

The bracket 5 may be held in the operative position shown in Fig. 1. For this purpose a locking member 10 is connected to the bracket 5, by means of a chain 11. The locking member 10 can engage a hook-shaped lug 12 which is turnably secured to the bracket by means of the pivot pin 8, it being understood that the lower end of said member 12 has a hook-shape. The other end 10a of the locking member 10 is also hook-shaped, as shown in Fig. 3, and said hook-shaped end 10a can engage the upper end of a lug 14 which is riveted or otherwise suitably secured to the adjacent lateral face of the standard 2. The inoperative position of said locking member 10 is shown at the right-hand side of Fig. 1.

As shown in Fig. 5, the locking member 10 also serves to lock the bracket 5 in its inoperative position, in which it is perpendicular to the head of the standard 2. The device is also provided with intermediate guard members 15, which are secured by chains 16a to the standard 2. The intermediate guard members 15 are pivotally connected to links 16 and said links 16 are pivotally connected to bottom guard members 17. Each bottom guard member 17 is turnably connected by means of a hinge 18 and a hinge-pintle 19 to the bottom of the standard 2. The bottom edge of each bottom guard member 17 substantially abuts the base 1.

As shown in Fig. 1, each of the standards 2 has a pair of bottom guard members 17 associated therewith. One of said guard members 17 is pro-

vided at its bottom with a turned or hook-shaped edge 17a. The other is provided at its top with a turned or hook-shaped edge 17b.

Referring to Fig. 2, it can be seen that adjacent 5 guard members 17 of adjacent units can be caused to interengage by means of said edges 17a and 17b.

As shown in Fig. 1, each bottom member 17 may be adjustably secured to the adjacent member 10 of the hinge 18, in order to allow for any inequalities in the floor. For this purpose each member 17 is provided with a vertical slot 20 and a pin 21a slidably retains the members 17 in position, while permitting a limited vertical movement 15 thereof. One of the upper guard members 7 of each unit is provided with an ordinary clamp 21 by means of which adjacent upper members 7 of adjacent units may be clamped to each other.

As shown in Figs. 1 and 6, additional means 20 may be provided for connecting each standard firmly to the floor. These additional means may comprise a bent strut 23, whose upper end is connected to the standard 2 by means of a clamping device 24.

25 As shown in Fig. 6, the lower end of said strut 23 is laterally offset, and said lower end may be connected to the floor by means of fastening devices 3a.

The guard arms can be upwardly turned while 30 the brackets 5 and 5a are held parallel to each other, and the parts can then be connected by means of a chain 26 which is connected to the top of the standard 2.

Referring to Fig. 6, it can be seen that the 35 guard arms of the units can be held parallel to each other in order to guard the long side of an opening. Likewise, said guard arms can be held perpendicular to each other, in order to apply the unit to the corner of an opening.

40 When the parts of the device are in the positions shown in Fig. 7, the brackets 5 are perpendicular to the head of the standard 2, so that the device is then very compact.

I have referred to the members 5 and 5a as 45 bracket members, but it is clear that they could be replaced by any suitable form of hinge device.

As shown in Fig. 1, when the bottom guard members 17 are turned upwardly, they may abut the stop members 9.

50 I have shown a preferred embodiment of my invention, but it is clear that numerous changes and omissions can be made without departing from its spirit.

I claim:

55 1. A safety guard unit comprising a standard, two bracket members turnably connected to said standard, said bracket members being turnable about vertical axes, and a guard member turnably connected to each of said brackets, said guard members being turnable around horizontal axes with respect to said brackets, and means 60 for holding said guard members in fixed position relative to said standard.

65 2. A safety guard unit comprising a standard, two bracket members turnably connected to said standard, said bracket members being turnable

about vertical axes, and a guard member turnably connected to each of said brackets, said guard members being turnable around horizontal axes with respect to said brackets, said bracket members having means adapted to hold said guard members fixed with respect to said bracket members.

3. A safety guard unit comprising a standard, two bracket members turnably connected to said standard, said bracket members being turnable about vertical axes, and a guard member turnably connected to each of said brackets, said guard member being turnable around horizontal axes with respect to said brackets, and means adapted to hold said bracket members in a plurality of positions relative to said standard.

4. A safety guard device comprising a T-shaped standard, said standard having a web and a head, two bracket members turnably connected to the head of said standard and turnable about vertical axes, a guard member turnably connected to each of said bracket members about horizontal axes, and holding means adapted to hold each said bracket member parallel to and also perpendicular to the head of said standard.

5. A safety guard unit comprising a standard, two bracket members turnably connected to said standard, said bracket members being turnable about vertical axes, and a guard member turnably connected to each of said brackets, said guard members being turnable around horizontal axes with respect to said brackets, said standard having at the upper end thereof means adapted to hold said guard members in upwardly directed position.

6. A safety guard device comprising a standard, and a pair of guard members turnably connected to said standard, one of said guard members having a hook-shaped bottom edge, the other guard member having a hook-shaped top edge.

7. A safety guard device comprising a base, a T-shaped standard connected to said base, said standard having a head and a web perpendicular to said head, two bracket members turnably connected to said head intermediate the top and bottom of said standard, two hinge members turnably connected to said standard adjacent the bottom thereof, an upper guard member turnably connected to each of said bracket members, a lower guard member turnably connected to each of said hinge members, said guard members being turnable upwardly with respect to said bracket members, and said hinge members, said bracket members having stops at their outer faces, said stops being adapted to retain the upper guard members in horizontal position, holding means adapted to hold said bracket members parallel to said head and also perpendicular to said head, one of said bottom guard members having a bottom hook-shaped edge, and the other of said bottom guard members having a top hook-shaped edge, said standard having adjacent the top thereof means adapted to retain the upper guard members when the same are upwardly turned.
